UNITED STATES PATENT OFFICE.

CHARLES H. MYERS, OF BUFFALO, NEW YORK.

MIXER FOR GASEOUS FLUIDS.

1,075,597.

Specification of Letters Patent. Patented Oct. 14, 1913.

Application filed February 24, 1910, Serial No. 545,776. Renewed March 7, 1913. Serial No. 752,787.

To all whom it may concern:

Be it known that I, CHARLES H. MYERS, a citizen of the United States, residing at Buffalo, in the county of Erie and State of New York, have invented a new and useful 5 Mixer for Gaseous Fluids, of which the following is a specification.

This invention relates to means for mixing air and gas prior to the admission of the 10 same to the combustion chamber of an explosive engine, and consists in certain novel features which will be hereinafter first fully described and then pointed out in the claims.

In the annexed drawings, which fully 15 illustrate my invention, Figure 1 is a side elevation of the improved device. Fig. 2 is a central vertical section of the same. Fig. 3 is a horizontal section taken on the line 3—3 of Fig. 2. Fig. 4 is a detail perspective view 20 of the outer sleeve. Fig. 5 is a detail perspective view of the inner sleeve. Fig. 6 is a detail perspective view of the tube constituting the passage for the gas. Fig. 7 is a detail perspective view of the clamping 25 nut.

In the drawings, I have indicated a portion 30 of a gas generator or carburetor 1, which may be of any desired type, being shown only for the purpose of indicating 35 the application of my invention, and the construction of which it is not necessary to describe. Leading from any convenient point 40 of the generator is an elbow or tube 2 to the end of which is secured a cup-shaped coupling 3 containing a screen 4 to filter the gas on its passage to the engine, and in the base of this coupling I secure a plate 5 in which is centrally fitted a gas tube 6 which 45 may be of any desired dimensions and is provided at a point about midway its ends 50 with openings or ports 7, while to its lower end is secured a coupling 8 from which the pipe 9 leads to the combustion chamber of the engine.

Disposed concentrically around the gas 55 tube 6 but spaced from the same is an air tube 10 provided with notches or ports 11 at its lower end, and around the said air tube and fitting closely against the same is a 60 damper or regulating sleeve 12 provided at its lower end with notches or ports 13 adapted to register with the ports 11 in the air tube 10, or to register with portions of the tube between the said ports so as to cut off 65 the flow of air, as will be readily understood. At its upper end this damper or regulating

sleeve is provided with a milled flange or head 14, by means of which it may be rotated upon the said sleeve 10 to adjust the device so as to control the admission of air. 60

My device is intended more particularly for use in connection with motor cycles and I, therefore, purpose to have the damper held in its position after it has been adjusted so as to obtain the most satisfactory 65 results from the engine, and to this end I mount a securing nut 15 upon the gas tube 7, which nut is adapted to be turned home against the lower ends of the air tube 10 and the damper 12 so as to bind the same 70 against the plate 5 and the coupling 3 sufficiently to hold them in their adjusted positions.

The operation of the device will be readily understood. The gas is drawn through the 75 gas tube 6, the coupling 8, and the pipe 9, into the explosive chamber of the engine, in the ordinary manner by the suction of the engine. Air admitted through the registering ports 11 and 13 will pass up between the 80 gas tube and the air tube and enter the gas tube through the port 7 so as to mingle with the gas and become thoroughly mixed therewith, so that when the mixture is admitted 85 into the combustion chamber of the engine, it will have the proper proportions of air and gas to obtain the desired results. By having the ports in the gas pipe arranged some slight distance above the lower end thereof, the air is not drawn directly to the 90 engine but will travel a short distance with the gas so as to be thoroughly commingled therewith when it enters the engine.

The coupling 8 is in the form of a T-fitting and on the outer end of the said coupling I secure a cap or thimble 16 provided with openings 17 in its side and having a valve stem 18 slidably mounted in its outer end. A valve 19 is carried by the said stem and is normally held against the end of the 95 coupling 8 by a spring 20 coiled around the said stem between the valve and the end of the thimble, as clearly shown in Fig. 2. Should there be an excessive back pressure 100 from the engine, this pressure will overcome 105 the tension of the spring 20 so as to unseat the valve, and the back-fire or unconsumed gases will consequently escape through the openings 17. All liability of any damage occurring to the engine is thus obviated. 110

My improved device is extremely simple in its construction and its advantages are

thought to be obvious. The parts can be readily assembled and the damper can be adjusted by means of the milled head without the rider being obliged to dismount and the frictional engagement of the retaining nut with the lower end of the damper will suffice to hold it in the position to which it has been adjusted. Damage to one part of the device will not necessarily involve the replacement of any other part.

Having thus described the invention, what I claim as new, and desire to secure by Letters Patent, is:—

1. In a device for the purpose described, a gas tube, an air tube surrounding the gas tube and provided with notches at one end constituting ports, the gas tube and air tube communicating, a damper on and rotatable about the air tube and provided with matching notches constituting ports, a closure for the end of the air tube and of the damper remote from the end provided with the notches, a closure for the notched ends of the air tube and damper movable toward and from the first named closure to lock the damper against rotation and to release it to rotation in accordance with the direction of movement of the second named closure, and means for supporting the closures.
2. In a device for the purpose described, an air tube having ports at the lower end, a damper rotatable on the air tube and provided with matching ports, and a gas tube interior to and concentric with the air tube and provided with ports intermediate of the length of the said air tube, and an adjustable member mounted on the gas tube and adjustable in the direction of the longitudinal axis thereof into clamping relation to the damper, said adjustable member constituting a closure for the lower ends of the air tube and damper.
3. The combination of a gas tube having ports, a supply coupling communicating with the upper end of the gas tube, an air tube arranged concentric with the gas tube and spaced therefrom and provided with ports, a damper rotatably fitted on the air tube and provided with ports adapted to register with the ports in the air tube, and a nut fitted on the gas tube and bearing against the lower ends of the air tube and the

damper to clamp the same against the coupling on the upper end of the gas tube.

4. The combination of a coupling, a plate 55 secured within the same, a gas tube centrally fitted to the plate and communicating with the interior of the coupling, and provided with ports at an intermediate point of its length, an air tube spaced from the gas tube 60 and concentric with the same and having ports at its lower end, a damper or regulating sleeve fitting the air tube closely and provided with ports registering with the ports of the air tube, a nut threaded on the 65 gas tube and adapted to bear against the lower ends of the damper and air tube, and a milled head on the damper by which it may be rotated.

5. The combination of a coupling, a gas 70 tube centrally fitted to and communicating with the interior of the coupling and provided with ports, an air tube spaced from the gas tube and concentric with the same and having ports at its lower end, a damper 75 or regulating sleeve fitting the air tube closely and provided with ports registering with the ports of the air tube, a nut threaded on the gas tube and adapted to bear against the lower ends of the damper and air tube, and means provided on the damper by which it may be rotated.

6. In a device for the purpose described, a gas tube having intermediate ports and an elongated threaded portion at one end, an 85 air tube concentric with and spaced from the gas tube and provided at one end with notches constituting ports, a damper exterior to the air tube and rotatable thereon and provided with matching notches 90 constituting ports, and an adjustable member mounted on the threaded end of the gas tube and constituting a closure for the notched ends of the air tube and damper, and adjustable on the portion of the gas tube carrying it to move into clamping relation to the damper.

In testimony, that I claim the foregoing as my own, I have hereto affixed my signature in the presence of two witnesses.

CHARLES H. MYERS.
